US00D604276S

(12) **United States Design Patent**
Schneider et al.

(10) **Patent No.:** **US D604,276 S**
(45) **Date of Patent:** **** Nov. 17, 2009**

(54) **ANTENNA ELEMENT**

(75) Inventors: **Richard E. Schneider**, Wildwood, MO (US); **John Edwin Ross, III**, Salt Lake City, UT (US)

(73) Assignee: **Antennas Direct, Inc.**, Eureka, MO (US)

(**) Term: **14 Years**

(21) Appl. No.: **29/305,294**

(22) Filed: **Mar. 17, 2008**

Related U.S. Application Data

(63) Continuation-in-part of application No. 12/040,464, filed on Feb. 29, 2008, application No. 29/305,294, and a continuation of application No. 12/050,133, filed on Mar. 17, 2008, which is a continuation-in-part of application No. 12/040,464.

(57) **CLAIM**

The ornamental design for an antenna element, as shown and described.

DESCRIPTION

FIG. 1 is a perspective view of the antenna element, showing our new design;

FIG. 2 is a front elevation view thereof;

FIG. 3 is a back elevation view thereof;

FIG. 4 is a bottom plan view thereof;

FIG. 5 is a top plan view thereof;

FIG. 6 is a right elevation view thereof;

FIG. 7 is a left elevation view thereof; and,

FIG. 8 is a perspective view thereof in use.

In the drawings, the broken lines depict environmental subject matter only and form no part of the claimed design.
